TRAFFIC CONTROLLING SYSTEM

Harry J. Littlefield, East Rockaway, N. Y.

Application April 1, 1930. Serial No. 440,700

3 Claims. (Cl. 177—324)

The present invention relates to visible signal street traffic-controlling systems having a neutral, warning or pedestrian period between the end of the "stop" period and the beginning of the 5 "go" period, and conversely between the ending of the "go" period and the beginning of the "stop" period, the purpose of this neutral period being to allow a brief time for the change of flow of traffic and to enable pedestrians already 10 crossing the street to reach the sidewalk before the traffic is again set in motion.

Several types of such systems are known employing either lights or semaphore arms as the 15 visible signal. One type employs a single lens before which are alternately placed red and green shutters, a dark interval between the red and green lights constituting the neutral period, another type employs two separate lights, one red and the other green with a dark interval between 20 them for the neutral period, another type is similar to the last but affords a four-way red indication for the neutral period, while yet a further type employs three lights, red, green and amber, the amber light constituting the neutral period. 25 This latter type may be operated in three different ways, the first being what is known as the amber overlap working in the sequence, green, green and amber, red, red and amber, green, etc.; the second being what is known as the non-overlap working 30 in the sequence, green, amber, red, amber, green, etc.; and the third being what is known as the green amber overlap or split-amber (synonymous terms) working in the sequence, green, green and amber, red, green, etc., that is the amber overlaps the green but not the red. The present invention is applicable to any of the aforesaid types 35 of traffic controlling systems or to any system which is to have the beginning and end of a neutral period announced by audible signals automatically timed in relation to visible signals.

An object of the present invention is to provide in conjunction with a traffic controlling system affording a neutral period means for automatically giving audible signals at the beginning and the 45 end of the neutral period in synchronization with the visible signals controlling the period.

A further object is to provide automatic coded police whistle signals at the beginning and end of the neutral period, e. g. a long police whistle blast at the beginning of the period and two short blasts at the end thereof.

A further object is to provide means for varying the interval between the beginning and end of the neutral period.

Yet another object is to provide an independ-

ent self-contained unit which may readily be fitted to any existing neutral period traffic-controlling system for the purpose of giving coded or other audible signals at the beginning and end of the neutral period.

60

Referring to the drawings:

Fig. 1 is a diagrammatic view of the invention as applied to a four-way, three-section, system operating on the split-amber principle. As such a system operating in this manner is well known, only sufficient of the wiring of the system has been shown to illustrate the pick-up from the amber circuit thereof to the present invention.

65

Fig. 2 is a diagrammatic cross-section through the motor operating the audible signals, showing the contact disc, reducing gear, and code-wheels upon the motor shaft.

70

Fig. 3 is a side view of the contact wheel.

Fig. 4 is a side view of the code wheels, one behind the other.

75

Fig. 5 is a diagrammatic sketch of the relay and the connections leading thereto from the traffic system and from the relay to the remainder of the unit.

80

Referring to the drawings, at the left-hand side of Fig. 1 are shown the red, green and amber lights of a four-way green-amber overlap or split-amber traffic-controlling system, the upper lamps 1, 2 and 3 being for the main street and the lower lamps 4, 5 and 6 for the cross street. As the wiring and other apparatus for operating the lights of such a system are well known, only sufficient thereof is shown as is necessary to illustrate the present invention. As will be seen, all the lights, both upper and lower, operate with a common return wire 7, while the upper red light 1 and the lower green light 6 have a common feed wire 8 and the upper green light 3 and the lower red light 4 have a common feed wire 9. The upper and lower amber lights 2, 5 are in separate circuits, fed, respectively, by lead-in wires 10 and 11, both of which are energized through the medium of the contact 12 according to whether it is moved to the left or right in a manner well known in the operation of the lights of the controlling system.

85

100 All the foregoing relates to apparatus well known in the prior art and I will now describe the present invention as applied thereto, which broadly comprises means for giving automatic audible signals at the beginning and end of the neutral period which are in synchronism with the visible signals governing this period. For this purpose I provide a synchronous or variable type, small, single phase motor A, a two-stage volume air-blower and motor E, and an electromagneti-

95

105

air-blower and motor E, and an electromagneti-

110

- cally operated air valve F, which controls a standard type police traffic whistle G. The shaft S' of motor A drives, through a variable gear reduction unit R, a shaft S², on which are mounted for rotation therewith three discs A⁵, B³ and B⁴. The disc A⁵ has a notch 13 in its periphery, while the disc B³ has a long cam projection 14, and the disc B⁴ two short cam projections 15, 16, all for a purpose to be hereinafter explained. The wires 10 L¹, L² are the lead-in and lead-out wires, respectively, for the current which operates the motor A, blower-motor E and the electro-magnetically operated valve F. This current supply is controlled by a sensitive, balanced relay C, specially 15 designed to operate on a current of very low value, which is less than that required to operate the amber lights of the controlling system. This low value current for operating the relay is obtained from the lighted amber light circuit by one or 20 other of the wires 17, 18, as the case may be. The relay C has a single-pole double-throw contact C⁷, C⁸ and two pairs of stationary contacts C³—C⁴ and C⁵—C⁶, which are provided so that the device 25 may be operated irrespective of whether the occurrence of the neutral period of the controlling system is brought about by the opening or the closing of a circuit. If the former is the case, the leads Y¹, Y² are connected to relay contacts C⁵—C⁶ as clearly shown by the dotted lines d¹ 30 and d² in Fig. 5, while if the latter is the case—as in the embodiment of the invention herein described and illustrated—they are connected to relay contacts C³—C⁴ as clearly shown by the solid lines D¹ and D² in Fig. 5.
- 35 The operation of the invention is as follows: Let us assume that in the operation of the visible signals of the controlling system the top green and bottom red lights are lighted by current supplied through the lead 9. The next step in the 40 cycle of operation of the visible signals would be the appearing of the amber light 2 upon the main street, which overlaps the green light 3, thus inaugurating the neutral or pedestrian period. This amber light upon the main street is lighted 45 by the contact 12 being moved to the right to engage the lead 10. Immediately this takes place, current is shunted from the lead 10 by means of the lead 17 through the relay C, and back through the lead 18 to the return lead 7 of the lighted 50 amber circuit. It will be noticed that in passing back to the lead 7 the shunted current passes through the dead amber lamp or lamps 5 of the cross-street, which lamp or lamps are, therefore, used as a resistance in series with the relay C; and as the relay is designed to operate upon much 55 less current than that required by the lamp, the relay operates without lighting the off amber lamp, which in the case under discussion is the lamp 5.
- 60 Immediately the relay C is energized the armature thereof bridges the contacts C³, C⁴, thus closing the circuit:—lead L¹, lead 19, terminal E², motor of blower E, terminal E¹, leads 20, Y², relay contacts C³, C⁴, leads Y¹ to return wire L², thus starting up the motor of the volume blower E. Simultaneously the circuit:—leads L¹ and 23, terminal A³, motor A, terminal A⁴, leads 22, 21, Y², relay contacts C³, C⁴, lead Y¹, to return lead L² is completed, thus starting up the motor A. As 65 soon as the motor starts it revolves the contact disc A⁵, which lifts the contact A², normally resting in the notch 13, into engagement with the contact A¹, thus maintaining circuits through the motor A and the motor of the blower-motor E for a complete revolution of the disc A⁵, no matter 70

whether the relay C is energized or not. The reason for this will be explained later.

As the discs B³, B⁴ are rigidly secured upon the same shaft as the disc A⁵, they will rotate therewith. Thus, as soon as the motor A starts up, the cam 14 upon the disc B³ lifts contact B² into engagement with contact B¹ and completes the circuit:—leads L¹, 23, 26, terminal F², coils of electromagnetically operated valve F, terminal F¹, lead 25, contacts B², B¹ to return lead L², with the result that a long blast upon the whistle G is produced. The length of this blast depends upon the peripheral length of the cam 14, and as soon as this cam passes the contact B² the latter drops back and breaks the circuit and so silences the whistle. The discs B³ and B⁴ continue to revolve until the cam 16 on disc B⁴ engages contact B² and again completes the circuit to cause a short blast upon the whistle governed in duration by the peripheral length of the contact 16. Similarly, continued rotation of the discs B³ and B⁴ causes the cam 15 to effect another short blast upon the whistle. The time interval between the beginning of the first blast and the end of the last blast depends, of course, upon the speed of rotation of the discs B³ and B⁴ and the peripheral distance between the forward end of the cam 14 and the rear end of the cam 15. As it is the object of the present invention to provide means for emitting an audible signal at the beginning and end of the neutral period determined by the visible signals, it will be obvious that the aforesaid factors governing the time interval between the audible signals will be arranged so as to make said time interval agree 110 with the length of the neutral period fixed by the visible signals. Should the duration of the neutral period, as governed by the visible signals, be altered, the time interval of the audible signals may readily be changed to agree therewith 115 by adjusting the discs B³, B⁴ relatively to each other. For this purpose the discs B³ and B⁴ are so mounted on the shaft S² as to enable them to be shifted by turning them relatively to each other and to the shaft, the discs being then 120 clamped in the desired relation by a nut S³. In the normal position of the apparatus the forward end of the cam 14 rests against the contact B² ready to lift the same as soon as the motor A starts up.

From the foregoing description it is clearly evident that upon the closing of either of the amber circuits thus lighting the amber lights therein and initiating the neutral period, the police whistle G simultaneously emits a long blast, and that 130 upon opening of the said amber circuit and so ending the neutral period the whistle will simultaneously emit two short blasts. This gives a definite audible warning in conjunction with the visible signals, and where an automobilist is 135 not law-minded enough to respect the visible signal he is forcibly reminded by the audible signal, and it is believed that fewer autoists will attempt to beat out the amber light or neutral period, which practice is the cause of many accidents to both automobilists and pedestrians. Further, as the audible signals are in synchronization with the visible signals, no lost time will be incurred.

From the above description it will be seen that 145 the cam 15 passes the contact B² at the moment the amber light circuit is opened, with the resultant de-energizing of the relay C and the consequent stoppage of the feed from L¹ through the relay to the motor A. It is the function of the 150

contact disc A⁵, therefore, to maintain a circuit through the motor A until the motor has brought the apparatus to its normal position with the forward end of the cam 14 resting against the contact B², at which instant the contact A² drops into the notch 13 of disc A⁵, thus de-energizing the motor A and bringing the apparatus to rest.

The invention may be constructed as an integral part of traffic-controlling systems, or it may 10 be constructed as a separate complete unit adapted to be fitted to traffic-controlling systems already in use. Its applicability to any of a large number of types of systems is one of the distinguishing features of the invention.

15 From the foregoing description it will be evident that the terms "synchronous", "synchronization" and the like are not used in a strictly limited sense, since while the operation of the audible signals is predetermined so as to recur 20 in a definite though variable manner in the cycle of operation of the combined system, the sounding of the audible signals is not necessarily coincident with the changes in the visible signals.

The invention has been illustrated in connection 25 with a split-amber traffic signal, and it has been thought unnecessary to illustrate other types of visible signals, or to illustrate the wiring of a complete system including transmitter timers, receiver timers and the like. There are numerous types of controls for timing or operating 30 traffic signals, such as the induction timer, the synchronous motor timer, the impulse timer, and the traffic operated control, each of these, in turn, embracing numerous forms and modifications. The existence of a suitable control is to 35 be understood in connection with the drawings, also the duplication of the visible signals, and of the associated audible signal unit of this invention, at the various intersections which may be subject to the general system. My invention is 40 independent of the particular mode of operation of the system with which it is used, considered as a whole, since as previously stated in any visible signal system which provides for a neutral period one of two things must take place, namely 45 either an electrical circuit is closed or an electrical circuit is opened, and all that is necessary is to make the pick-up connections 17, 18 to connect the audible signal unit.

50 I claim:

1. In a traffic-controlling system having neutral period lights in two-directions, an audible

signal device, electrical means for automatically causing said device to emit audible signals at the beginning and end of the aforesaid neutral period, a relay and means through which said relay controls said electrical means, said relay being designed to operate upon a current less than that required to give visibility to the neutral period lights, and a circuit for said relay fed from that of the lighted neutral period lights and including the dead neutral period lights in series resistance with the relay. 80

2. In a traffic controlling system, the combination with a set of traffic lights and electrical means for operating the same for the control of traffic and including a neutral period, of a traffic whistle, a blower connected with said whistle, a motor for driving said blower, an electromagnetic valve operable for controlling the sounding of said whistle by the blower, a code wheel for controlling said electromagnetic valve to sound the whistle according to a predetermined sequence within said neutral period, a motor for rotating said code wheel, a circuit for energizing said motors and said electromagnetic valve, means interconnected with the means for operating the traffic lights for initially completing circuits through said motors during the neutral period, locking circuits for said motors, and means for maintaining said locking circuits for a predetermined movement of said code wheel. 90

3. In a traffic controlling system, the combination with a set of traffic lights and electrical means for operating the same for the control of traffic and including a neutral period, of a traffic whistle, means for supplying said whistle with aeriform fluid to sound the same, an electromagnetic valve operable for controlling the sounding of said whistle by the said aeriform fluid, a code wheel for operating said electromagnetic valve to sound the whistle according to a 100 predetermined sequence within said neutral period, a motor for rotating said code wheel, a circuit for energizing said motor and said electromagnetic valve, means interconnected with the means for operating the traffic lights for 110 initially completing a circuit through said motor during the neutral period, a locking circuit for said motor, and means for maintaining said locking circuit for a predetermined movement of said code wheel. 115
